COSMETIC APPLICATOR

Chester H. Braselton, New York, N. Y.

Application December 26, 1947, Serial No. 793,993

6 Claims. (Cl. 206—56)

1

This invention relates to cosmetic applicators of the general type shown in my copending applications, Serial No. 699,025, filed September 24, 1946, entitled "Lipsticks", now Patent No. 2,457,342; Serial No. 699,026, filed September 24, 1946, entitled "Retractable Lipstick", now Patent No. 2,565,346; Serial No. 751,035, filed May 28, 1947, entitled "Non-Retractable Lipstick"; Serial No. 755,607, filed June 19, 1947, entitled "Manual Feeding Lipstick", now abandoned; Serial No. 756,598, filed June 24, 1947, entitled "Manual Feeding Retractable Lipstick"; and Serial No. 782,536, filed October 28, 1947, entitled "Lipstick," now Patent No. 2,545,444, in which the cosmetic material such as lip paste or rouge may be mechanically fed or forced toward the free or applying end of the cartridge containing the lipstick material, and relates to improved driving means whereby the feeding mechanism for the cartridge may be rotated with respect to the latter, and further relates to means whereby the feeding means and the cartridge are detachably held so that the feeding mechanism is in detachable driving relationship with the lipstick case enclosing the cartridge.

In the drawings,

Fig. 1 is an elevational view of lipstick container 1, with removable cap 2 in place thereon;

Fig. 2 is a side view of Fig. 1 with the cap 2 removed;

Fig. 3 is a longitudinal sectional view of Fig. 2;

Fig. 4 is a longitudinal sectional view of Fig. 2 taken at right angle to the view of Fig. 3 and on line 1—1 of Fig. 2, looking in the direction of the arrows;

Fig. 5 is a detailed view showing a modified form in which a ring surrounds the rectangular driving tubing and is adapted to fit within the lipstick casing;

Fig. 6 is a perspective view of a non-circular driving means attached to the feeding mechanism;

Fig. 7 is a longitudinal sectional view similar to Fig. 3 but showing a modified form of driving means for the feeding mechanism;

Fig. 8 is a view similar to Fig. 4 but a longitudinal sectional view of the form shown in Fig. 7, taken on the line 1—1 of Fig. 7, looking in the direction of the arrows;

Fig. 9 is a perspective of the non-circular driving means for the feeding mechanism of Figs. 7 and 8;

Fig. 10 is a perspective view of the non-circular driving and retaining means of Figs. 7 and 8 for cooperation with the driving means of Fig. 9;

2

Fig. 11 is still another modified form of driving and retaining means for the feeding mechanism;

Fig. 12 is a longitudinal sectional view of Fig. 11 taken at right angles thereto on the line 1—1 of Fig. 11 looking in the direction of the arrows;

Fig. 13 is a perspective view of the non-circular driving means for the feeding mechanism of Figs. 11 and 12;

Fig. 14 is a perspective view of the non-circular hollow driving means for the means shown in Fig. 13;

Fig. 15 is a view similar to Fig. 14, but showing the spring retaining means in place thereon; and

Fig. 16 is a perspective of the spring retaining means per se, shown in Fig. 15.

Referring to the drawings of Figs. 1 to 4, 1 is a lipstick container adapted to hold a lipstick casing cover 2 thereon. The container 1 has a shoulder base 3 in which the lower end of the container 1 fits and is held. 4 represents a cartridge containing lipstick paste or rouge and having an open ended and flat portion 5, and an open ended inclined portion 6 adapted to form two diverging frames for containing the lipstick material at the working end, so as to provide a projecting ridge of lipstick material transverse of the cartridge at the junction of the two planes similar to the ones shown in my above referred to applications.

30 The cartridge 4, Figs. 3 and 4, as shown in some of the above pending applications, has a rotatable circular closure 7 at the lower end rigidly attached to a feeding screw 8, adapted when the screw is turned to force the plunger 9 up or down.

35 Lipstick paste or rouge 10 is mounted in the cartridge above the plunger and may be forced toward the working end of the cartridge as the plunger is slowly fed upwardly when the screw 8 is rotated with respect to the cartridge. The end closure plate 7, to which the screw 8 is attached, is adapted to fit into the counterbored portion 11 in the lower ends of the cartridge which is then spun over the bottom edge of the closure plate 7 so that the plate and screw may

40 rotate with respect to the cartridge 4, but be prevented from longitudinal movement with respect to the cartridge 4.

45 In the form shown in Figs. 1 to 6, I mount axially on the bottom end of the plate 7 a non-circular block 12 having a hole 13 therethrough. The block 12 may be fastened on the outer surface of the plate 7 by soldering, welding or any other conventional manner. In the hole 13 through the driving block 12, I place a rod of rubber 14, or

50 other elastic material, which passes through the

block and projects slightly on both ends from the side of the block. This block, with its slightly yielding projecting portions of rubber or other material, is adapted to be positioned inside a hollow receiving tube 15, the outside surface of which is adapted to be soldered or otherwise fastened to the inside of the base 3 for permanent location. The base 3 has a bored-out portion 16 in which is located the lower end of casing 1 which is permanently fastened therein.

From the above it will appear that the cartridge 4 containing its base and feeding mechanism and driving block 12 with protruding friction portions of material 14, may be inserted in the casing 1 and readily removed therefrom, and when inserted therein in the position shown in Figs. 1 to 4, a driving relationship will exist between the square driving block 12 and the square hollow tubing 15. It will be further observed that the projections of material 14, being of rubber or other yielding material carried by the driving block 12, will engage the inner walls of two opposing inner surfaces of the driving tube 15 so that the cartridge with its driving block 12 will be frictionally, but sufficiently, held in place by the friction material 14 serving as a frictional holding means to retain the cartridge in place in the casing 1 until removal is desired. At the same time, when the cartridge is in place in the cartridge 4, the driving block 12 will be in driving relationship with the hollow tube 15 such that rotation of the cartridge 4 with respect to the casing 1 and casing base 3, will serve to provide rotative drive through the tube 15 and block 12 to the end of the closure plate 7 having fixed to it driving screw 8 on which is engaged the plunger 9. The plunger 9 is notched to contact spline 17 mounted longitudinally against the inner wall of the cartridge 4. This non-rotative connection between plunger 9 and the cartridge 4, by virtue of the spline 17 and its keyway connection in the plunger 9, which prevents rotation of the plunger with respect to the cartridge 4, causes the latter to move longitudinally in the cartridge 4 when the screw 8 is rotated. This movement of the plunger up or down is caused whenever rotative movement of the screw 8 and its driving block 12, with respect to the cartridge wall 4, is effected. It is thus seen that in this form I provide a cartridge which may be yieldingly and frictionally held in place and in driving relationship to the lipstick case adapted to hold the removable cartridge and yet provide a convenient detachable driving connection for the cartridge with respect to the lipstick case.

In Fig. 5 I have shown a modified form from that shown in Figs. 3 and 4 in which the hollow driving tube 15 is surrounded by the section of a circular tube 18, the inner diameter of the tube 18 adapted to fit the large diagonal of the driving tube 15 and surround the same. The outer part of the tube 18 is adapted to fit within the lower end of the casing 1 and be soldered or fastened thereto, and thus aid in locating the hollow driving tube 15.

Fig. 6 merely shows a perspective of the driving block 12 rigidly attached to the feeding mechanism of the cartridge with its rubber projections 14 extending from the opposite flat surfaces of the driving block.

Figs. 7 to 10 show modified forms of detachable driving mechanism for the lipstick cartridge. In this form the description is the same as that of Figs. 1 to 4 except that the squared driving block 19 fixed to the bottom surface of the end

closure plate 7a, in turn fastened to the feeding screw 8a, instead of having a frictional rubber rod extending through the same, is provided with four bevelled notches 20 in one plane at the corners of the square driving block. Also, just below these notches the extreme ends of the edges are bevelled at 21. This block is soldered or otherwise fastened to the end plate 7a in the same manner as described for the other views above in connection with the squared driving block. In these figures I provide for the driving block 19 to be driven by a hollow square tubing 22, the inside dimensions of the hollow tubing being such as to readily receive the driving block 19. Two opposite corners of the tubing 22 are slotted at 23 from extreme peripheral dimensions sufficiently inwardly to come across the inside corners of the tube. One of the other corners of the driving tube 22 is notched partially at 24 and in these three notches is adapted to pass a hairpin spring 25, the closed end of which is adapted to fit in the notch 24 so as not to project beyond the edge 24a of the hollow tube 22 at this edge. The legs of the hairpin spring 25 are positioned in the slots 23 of the hollow tube 22 so that the spring sides of the hairpin project across the inside opposite corners of the hollow tubing to form a latching means to latch the driving block 19 therein when the same is pushed down into the hollow tubing 22 and the two sides of the hairpin spring 25 are forced back and then engage the bevelled notches 20 in the driving block 19.

I mount the hollow square receiving tube 22 with its hairpin spring 25 in place in the bored out inside hollow of base 3a by means of solder or other suitable adhesive, as shown in Fig. 8. It is seen that the lower extent of container sheath 1' in combination with the squared hollow receiving tube 22, provides a construction very similar, in general form, to the ring shown in Fig. 5. Under such mounting conditions the lower inner surface of sheath 1', in contact with the corners of the square block such as 24a, Fig. 10, provide means for holding the hairpin spring 23 in the slots of the squared tube. With this arrangement insertion of the block 19 into the lipstick casing, and therefore into the square receiving tube 22, through the action of the bevels 21 of said block causes the legs of the hairpin spring 23 to yield outwardly from the center of the squared block in the provided slots 23. Further insertion of the block then allows the hairpin spring to latchingly engage the notches 20, as previously described.

In Figs. 11 to 16 I have shown a further modification of detachable driving means for the lipstick cartridge. In this form the cartridge and lipstick case is the same as in the preceding forms, but the driving block 26 fastened on the bottom end of the end plate 7b, as shown in Fig. 13, has bored latching depressions 27 on the four surfaces of the driving block, these depressions being in the same plane and equidistant from the end of the block. A driving tube 28 is adapted to receive block 26 and may be fastened or soldered at its bottom end to the bored-out portion of the base 3b, as in the case of the other driving tubes. In this form, however, the edge of the driving tube 28 has a notched-out portion 29 in its two opposite walls, and also has two opposing holes 30 in the corresponding walls just above the notches. I mount a U-shaped spring 31 in the notches so as to go across the lower end of the tube 28 in the notches, and this U-shaped spring has two opposing projections 32

which are adapted to be positioned in the holes 30, the projections 32 adapted to project inside the inside surface of the hollow tube 28. The spring is mounted in place before the hollow tube is fastened to the bored-out portion of the base 3b and when in place the U-shaped spring, with its projections 32, serve as yielding latching means which are bevelled at the opposing ends. Thus it will be seen that when the driving block 26 of Fig. 13 is forced into the hollow tube 28 the spring projections 32 in U-shaped spring will be forced outwardly, allowing the driving block to be pushed completely in place when the latching projections 32 will engage either of the two sets of opposing depressions 27 in the driving block 26. By this construction I provide a detachable driving relationship between the driving block on the bottom end of the cartridge and the driving tube mounted on the bottom of the inside base of the casing. When the block is in position the U-shaped spring with its projections extending through the holes in the driving tube cooperate with the driving block depressions as a latching means to hold the block and cartridge in place, and the non-circularity of the receiving tube 22 and the driving block 26 provides driving connections between the base and feeding screw for the lipstick cartridge.

From the above description it will be seen that I have provided a novel, cheap and practical detachable driving means for a lipstick cartridge for coupling the same to the casing, which will serve as a driving means for the mechanism of the cartridge. In the manner shown I form a practical but cheap construction for accomplishing this end. I have been able to eliminate considerable machine work caused by forming the driving connection out of square, square-sided or non-circular rod and corresponding polygonal or non-circular hollow tubing adapted to telescopically fit so as to provide a driving connection without too much cost for machine work. I have also provided a practical method whereby these non-circular driving means may be frictionally held together to retain the cartridge in place in the casing, and also a form in which they may be practically held together by yielding spring means, still retaining the driving connections capable of being formed from inexpensive stock.

Other advantageous applications of my invention described herein will suggest themselves to those skilled in the art, to which this invention relates, without, however, departing from the spirit and scope of the following claims.

What I claim is:

1. A cosmetic applicator comprising a casing, a cartridge enterable into said casing, said cartridge having a paste-feeding means therein including a portion rotatably fixed in the bottom of the cartridge and a square-sided plug extending therefrom, said casing having a square-sided sleeve-like socket in its base receiving said plug when said cartridge is entered into said casing, and said plug having a transverse bore therethrough and a rubber insert extending through and projecting from said bore for frictionally engaging opposed walls of said socket to retain

said cartridge in feed-driving relation to said casing.

5 2. A cosmetic applicator comprising a casing, a cartridge enterable into said casing, said cartridge having a paste-feeding means therein including a portion rotatably fixed in the bottom of the cartridge and a square-sided plug extending therefrom, said casing having a square-sided sleeve-like socket in its base receiving said plug when said cartridge is entered into said casing, and said plug having a rubber insert projecting therefrom for frictionally engaging a wall of said socket to retain said cartridge in feed-driving relation to said casing.

10 3. A cosmetic applicator comprising a casing, a cartridge enterable into said casing, said cartridge having a paste-feeding means therein including a portion rotatably fixed in the bottom of the cartridge and a square-sided plug extending therefrom, said casing having a square-sided sleeve-like socket in its base receiving said plug when said cartridge is entered into said casing, and said plug having a laterally projecting resilient element extending therefrom for frictionally 15 engaging a wall of said socket to retain said cartridge in feed-driving relation to said casing.

20 4. A cartridge for a cosmetic applicator, said cartridge comprising a sleeve-like body open at its upper end and having a paste-feeding means 30 therein including a portion rotatably fixed in its bottom, and said cartridge having a square-sided drive-connecting plug extending from said rotatable portion, said plug having a transverse bore therethrough and having a rubber insert extending 35 through said bore and projecting laterally from said plug.

25 5. A cartridge for a cosmetic applicator, said cartridge comprising a sleeve-like body open at its upper end and having a paste-feeding means 30 therein including a portion rotatably fixed in its bottom, and said cartridge having a square-sided drive-connecting plug extending from said rotatable portion, said plug having a rubber insert projecting therefrom for frictionally retaining 40 45 said cartridge in a casing.

6. A cartridge for a cosmetic applicator, said cartridge comprising a sleeve-like body open at its upper end and having a paste-feeding means therein including a portion rotatably fixed in its bottom, and said cartridge having a square-sided drive-connecting plug extending from said rotatable portion, said plug having a laterally projecting resilient element extending therefrom for frictionally retaining said cartridge in a casing.

55 CHESTER H. BRASELTON.
